UNITED STATES PATENT OFFICE.

WILBUR FISK OSBORNE AND CHARLES A. KELLY, OF ANSONIA, CONNECTICUT, ASSIGNORS TO THE UNION FABRIC COMPANY, OF ANSONIA, CONNECTICUT, A CORPORATION.

MACHINE FOR COVERING DRESS-STAYS.

SPECIFICATION forming part of Letters Patent No. 767,708, dated August 16, 1904.

Application filed May 16, 1904. Serial No. 208,177. (No model.)

To all whom it may concern:

Be it known that we, WILBUR FISK OSBORNE and CHARLES A. KELLY, of Ansonia, in the county of New Haven and State of Connecticut, have invented a new and useful Improvement in Machines for Covering Dress-Stays; and we do hereby declare the following, when taken in connection with the accompanying drawings and the figures of reference marked thereon, to be a full, clear, and exact description of the same, and which said drawings constitute part of this specification, and represent, in—

Figure 1, a broken side view of a machine for covering dress-stays constructed in accordance with our invention; Fig. 2, a top or plan view of the same; Fig. 3, a broken sectional view on the line *a b* of Fig. 1; Fig. 4, a side view of the lower feed-roll with clamp-disk removed; Fig. 5, a broken view of the right-hand end of the machine; Fig. 6, an enlarged sectional view through the frame, showing a side view of the cutter; Fig. 7, a view illustrating the arrangement of the wires with respect to the covering.

This invention relates to an improvement in covering dress-stays, and particularly to that class which consists of a wire stiffener covered on opposite sides with paper or cloth, the ends of the paper or cloth projecting beyond the ends of the wires, and is an improvement on the invention shown and described in Patent No. 488,288, granted December 20, 1892, to George O. Schneller. The machine of the Schneller patent was particularly adapted for covering a single wire, but might be used for covering two or more wires in the same strip; but in the use of such a machine in covering two or more wires, owing to the variation in the thickness of the wires, they will be fed irregularly, so that the ends will not stand in the same line.

The object of this invention is the construction and arrangement of feeding-rolls whereby two or more wires may be uniformly fed and compensate for variation in thickness; and the invention consists in the construc-

tion, as hereinafter described, and particularly recited in the claims.

In carrying out our invention we employ an upper feed-roll 2 and a lower feed-roll consisting of rings 3, 4, and 5, corresponding in number to the number of wires to be fed, the combined several rings also corresponding in width to the width of the upper feed-roll 2. These rings are mounted upon a hub 6, keyed to a shaft 7 and having a flange 8 somewhat smaller in diameter than the external diameter of the rings and against which the rings are held by a plate 9, the plate 9 and flange 8 forming, as it might be said, a groove in which the rings are placed. If three rings are employed, the internal diameter of the central ring corresponds to the diameter of the hub, while the internal diameters of the outer rings 3 and 5 are slightly greater than the diameter of the hub, so as to permit a certain amount of vertical movement thereon, and each of these outer rings is supported at the bottom upon rollers 10 and 11, mounted in a yoke 12, the yokes bearing upon springs 13. The other features of the machine are substantially the same as the patent before referred to except that the rollers will be of a width corresponding to the width of the stays to be formed. Thus the lower strand or ribbon 14, of paper, cloth, or other suitable material, passes over a roller 15, which applies glue to its upper face, and thence passes between folders 16 and between pressure-rollers 17 and 18, while the strand or ribbon 19 passes over the said roller 18, which unites it with the ribbon 14. The wires 20, fed by the feed-roll 2, are severed by a cutter 21, while the completed stay is severed from the strip by the cutter 22. The operating-shafts 23 and 24 are connected by gears 25, 26, and 27, the shaft 23 being driven by the usual pulleys 28. On the shaft 23 is a bevel-gear 29, meshing with a bevel-gear 30, which drives the shaft 7. On this shaft 7 is a gear 31, meshing with the gear 32 on the shaft 7^a of the feed-roller 2. Also on the shaft 23 is a bevel-gear 33, meshing with a bevel-gear 34, operating the pres-

sure-roll 17, which is geared with the roller 18. On the shaft 24 are cams 35 and 36, which respectively operate the cutters 21 and 22 through levers 37 and 38. As in the patent before referred to, the wires 20 are shorter than the strips of covering material 14 and 19. As the wires are fed between the feed-rollers the rings 3 and 5 will bear with yielding but continuous pressure against the roll 2, so that if there are any variations in the thickness of the wire it will not bind between the feed-rollers, and if one is thicker than the other two it will not prevent the other two from feeding, or if thinner than the other two it will be itself fed. We are therefore enabled to cover three wires in a single strip and have their ends in alinement.

Having fully described our invention, what we claim as new, and desire to secure by Letters Patent, is—

1. In a machine for covering dress-stays the combination with paper-feed rolls, of two wire-feed rolls, the lower feed-roll comprising a

hub and two or more rings upon said hub, said rings of greater diameter than the diameter of said hub, and means for supporting said rings, substantially as described. 25

2. A machine for covering dress-stays including an upper feed-roll and a lower feed-roll said lower feed-roll comprising a hub, a plurality of rings on said hub, one of the said rings closely fitting said hub and another of greater internal diameter than the diameter of the hub, a pair of rollers upon which said rings rest, a yoke supporting said rollers, and a spring beneath said yoke and tending to lift the ring against the upper feed-roll, substantially as described. 30 35

In testimony whereof we have signed this specification in the presence of two subscribers.

WILBUR FISK OSBORNE.
